UNITED STATES PATENT OFFICE.

ROBERT M. SYPER, OF LEONIA, NEW JERSEY.

DUMB-WAITER MACHINE.

1,129,434.

Specification of Letters Patent.

Patented Feb. 23, 1915.

Application filed March 30, 1914. Serial No. 828,162.

To all whom it may concern:

Be it known that I, ROBERT M. SYPER, a citizen of the United States, residing at Leonia, in the county of Bergen and State 5 of New Jersey, have invented certain new and useful Improvements in Dumb-Waiter Machines, of which the following is a specification.

My invention relates to elevating apparatus 10 and particularly to improvements in hand-operating dumbwaiters of the kind known as automatic dumbwaiters. Apparatus of this character has heretofore been provided in which the dumbwaiter is automatically locked in position when the lifting means is released.

The object of my invention is to provide improved automatic locking devices whereby the dumbwaiter may be automatically 20 retained in any desired vertical position in the hatchway.

My invention comprises devices whereby the apparatus is automatically locked either on the upward motion or the downward motion, and regardless of whether the dumbwaiter car is overbalanced by the counterweight or the reverse, whenever the hand-operating means, or other means for raising and lowering the car, is released.

Other objects of my invention reside in the construction of parts and combinations of elements hereinafter more fully described.

In order that my invention may be more 35 clearly understood, attention is hereby directed to the accompanying drawings forming part of the specification and illustrating a preferred embodiment of my invention.

Referring to the drawings, Figure 1 represents an end elevation of the entire operating mechanism, Fig. 2 represents a side elevation, and Fig. 3 represents a plan view of the same; Fig. 4 is a part elevation and part sectional view taken on line 4-4 of Fig. 3 representing the locking device in 45 free or inoperative position, Fig. 5 is a similar view representing the locking device in one locking position, the outer casing not being shown in this figure, Fig. 6 is a sectional view taken on line 6-6 of Fig. 4 and Fig. 7 is a perspective view of the locking lever shown in Figs. 4, 5 and 6.

Referring to the drawings, the rope sheave

1 is securely fastened to the shaft 2 which may be termed the driving shaft of the apparatus. The hoisting sheave 3 is loosely mounted upon shaft 2 and carries the rope 4, one end of which extends to and is fastened to the dumbwaiter and the other end of which is secured to the counterweight in 60 the well known manner. Rope 4 extends over a small deflector sheave 5 mounted on a shaft 6. Endless hand rope 7 runs in the groove of the rope sheave 1. The parts described are supported from a frame 8, on 65 which bearings 9 and 10 for shaft 2 are mounted, shaft 6 being supported as shown from frame 8 by bearings mounted in brackets 11, 12. A collar 13 on shaft 2 prevents endwise movement of sheave 3 upon shaft 70 2. A casing 14 is integral with or secured to the bearing block 10 in which the end of shaft 2 rotates. The automatic locking devices are contained within the casing 14.

Referring to Figs. 4, 5, 6 and 7 of the 75 drawings, a brake or locking band 15 is mounted within the annular surface of casing 14. This band is resilient and has two adjacent ends having lugs or jaws 16 and 17 formed thereon. A lever 18 is pivotally 80 mounted upon a pin 19 situated between jaws 16 and 17, this lever having a head or enlarged portion 20 situated between the said jaws, the lever also having a lug 21 upon its inwardly extending arm. When 85 the device is in unlocked position, the lever 18 is in the position illustrated in Fig. 4, in which the top and bottom surfaces of the head 20 of lever 18 are parallel to and contacted by the lower and upper surfaces of 90 jaws 16 and 17, respectively, of locking ring 15, the spring ring in this position bearing frictionally upon the inner surface of casing 14 but being free to rotate around in the same. When, however, the lever 18 is partly 95 rotated about pin 19 in a clockwise direction as shown in Fig. 5, the upper and lower corners 22 and 23 of head 20 of lever 18 press against the lower and upper surfaces, respectively, of jaws 16 and 17 to expand 100 ring 15 into locking engagement with the fixed casing 14. The construction to be described causes the placing of lever 18 in the unlocking position shown in Fig. 4 whenever the dumbwaiter car is being raised or 105 lowered and places the same in the locking

position shown in Fig. 5 whenever the raising or lowering actuation of hand rope 7 is discontinued.

An arm 24 is fixedly secured to shaft 2 by a suitable means such as set screw 25. Arm 24 carries upon the under side of its end an actuating lug 26. In Fig. 5, for the sake of simplicity, arm 24 is omitted, actuating lug 26 thereof alone being shown. Lever 18, 5 mounted on pin 19, has, as stated, on its inwardly extending arm a lug 21. This lever 18 is also formed with a curved arm 27, extending partly around shaft 2, and having an upwardly extending lug 28 formed at the 10 end thereof, both lugs 21 and 28 lying in the path of lug 26 upon arm 24. The sheave 3 has lugs or projections 29 and 30 formed thereon, as shown in Figs. 4, 5 and 6, and extending into the path of lugs 21 and 28 on 15 lever 18. An arm 31 is loosely mounted on shaft 2 and carries the pin 19, which is screwed into or otherwise secured to the free end of arm 31, the pin 19 being the pivot for locking lever 18 as previously 20 stated. A torsion spring 32 is mounted upon arm 31, one end of spring 32 engaging a pin or projection 33 on arm 31, while the other end of the spring engages lug 21 on lever 18, this spring always tending, by its 25 pressure on lug 21, to depress lever 18 into locking position as shown in Fig. 5.

Brake ring 15 is held in place longitudinally of the shaft 2 by a shoulder 34 on casing 14, on the one side of brake band 15 and 30 by an annular projection 35 extending from sheave 3, on the other side of the brake band.

In describing the operation of the device, it will be remembered that the dumbwaiter car is automatically locked regardless of 40 whether the car overbalances the counter-weight or whether the counterweight overbalances the car, when hand rope 7 is released on either upward or downward movement. Assuming first that the unbalanced 45 load on the sheave 3 is in such a direction as to tend to rotate sheave 3 in a counter-clockwise direction referring to Figs. 4 and 5, when the hand rope is released the lug 29 on the sheave 3 moves in a counter-clockwise 50 direction and contacting lug 21 on lever 18 oscillates lever 18 in a clockwise direction about pivot pin 19 into the locking position shown in Fig. 5, the spring 32 aiding this movement. In this position, the corners of 55 head 20 of lever 18 expand ring 15 into a tight engagement with the inner surface of casing 14, so that sheave 3 is locked in that position. The more lug 29 presses on lug 21, the more tightly will band 15 be forced into 60 engagement with casing 14, locking sheave 3 and holding the dumbwaiter car in position. Still assuming that the load on sheave 3 is in such a direction as to tend to rotate sheave 3 in a counter-clockwise direction referring 65 to Figs. 4 and 5, the action when the car is

to be raised is as follows:—The hand rope 7 is actuated in such a direction as to rotate shaft 2 in a clockwise direction. Lug 26 on arm 24 then comes into contact with lug 21 on lever 18, raising lever 18 into the unlocked position shown in Fig. 4, lug 29 on sheave 3 being moved slightly in a clockwise direction by lug 21. The pressure of band 15 on casing 14 is now sufficiently reduced so that band 15 can rotate within the casing, 70 and on continued rotation of the hand rope, the sheave 3, together with band 15 will be rotated in a clockwise direction raising the load, the power being transmitted from shaft 2 through lug 26 on arm 24 to lug 80 21 on lever 18 and thence to lug 29 on the sheave 3. When the hand rope 7 is released, the load actuating through lug 29 on sheave 3, aided by spring 32, again forces lever 18 into locking position. When it is 85 desired to lower the load in this case, the hand rope 7 is actuated in the opposite direction giving shaft 2 a counter-clockwise rotation. Lug 26 on arm 24 then contacts projection 28 on the end of arm 27 of lever 18, 90 lug 28 being so positioned that the contacting of this lug by lug 26 oscillates lever 18 about pin 19 in a counter-clockwise direction, head 20 of the lever 18 again being moved into its unlocking position as shown 95 in Fig. 4. Upon a continuation of this movement of the hand rope, the sheave 3, together with locking ring 15 is rotated in a counter-clockwise direction, the locking lever 18 being held in unlocking position by the 100 camming action of lug 26 on lug 28, and the sheave 3 rotating in the same counter-clockwise direction because of the pressure of the load on rope 4 in that direction. Assuming on the other hand that the effective load, 105 on rope 4 is in such a direction as to tend to rotate sheave 3 in a clockwise direction, when the hand rope is released the device is locked by lug 30 on sheave 3 contacting lug 28 on lever 18 and rotating lever 18 110 about pin 19 in a clockwise direction into the locking position shown in Fig. 5. It is obvious that the effect of lug 30 pressing upon lug 28 in a clockwise direction is the same as that exerted by lug 29 acting on lug 115 21 in a counter-clockwise direction. When now it is desired to unlock and raise the load, shaft 2 is turned in a counter-clockwise direction by the hand rope, lug 26 on arm 24 contacting lug 28 to cam lever 18 120 into its unlocking position. A continuation of this movement causes the rotation of sheave 3 in a counter-clockwise direction, by the pressure of lug 28 upon lug 30. When the actuation of the hand rope is stopped, 125 the pressure of lug 30 on lug 28 again locks the device. To lower the load in this case, shaft 2 is turned in a clockwise direction, lug 26 on arm 24 striking lug 21 on lever 18 to swing the lever into unlocking position, in 130

which it is held by the pressure of lug 26 on lug 21, sheave 3 and band 15 rotating in a clockwise direction and lowering the load so long as the operation of the hand rope in this direction is continued.

5 While I have described my invention as particularly relating to hand power dumbwaiters, it is evident that the device may be used for hand power elevators and also for 10 that type of elevator in which the rope 7 is actuated by power. It is also evident that my invention is not strictly limited to the exact details of construction described, but broadly includes equivalent means for attaining the desired ends.

15 Having now particularly described my invention, what I claim and desire to protect by Letters Patent is as follows:

1. In apparatus of the character described, 20 the combination with a shaft of means for raising or lowering a load applied to either side of said shaft, brake means for preventing movement of the load, spring means tending at all times to apply said brake 25 means, lever means, and means whereby the weight of the load on either side of said shaft acts on said lever means to apply said brake means whenever said raising or lowering means is not being operated, substantially as set forth.

30 2. In apparatus of the character described, the combination with a shaft, of means for rotating the same, a revolute member loose on said shaft, a stationary member, a brake 35 member within the same, means for locking said revolute member when said brake member is operated, and means comprising a member secured to said shaft actuated by the revolution of said shaft in either direction 40 for disabling said brake member, substantially as set forth.

35 3. In apparatus of the character described, the combination with a shaft, of means for rotating the same, a revolute member loose 45 on said shaft, a stationary member, a brake band within the same, means for applying said brake band whenever said shaft is at rest and means including a member secured to said shaft for loosening said brake band 50 and connecting said revolute member to said shaft when the latter is rotated in either direction, substantially as set forth.

40 4. In apparatus of the character described, the combination with a shaft, a sheave secured to the same, a rope running over the sheave and having one end secured to a car and the other to a counterweight, of means for rotating the shaft, a revolute member loose on said shaft, a stationary member, a 45 brake band within the same, means for applying said brake band whenever said shaft is at rest and thereby locking said revolute member, and means independent of the direction in which the load tends to turn 55 said shaft actuated by the revolution of said

shaft in either direction for loosening said brake band and connecting the same and said revolute member to said shaft for rotation thereby, substantially as set forth.

5. In apparatus of the character described, 70 the combination with a power shaft, of a revolute member loose thereon, a brake device controlling the operation thereof, means for applying said device to lock said member whenever the latter tends to rotate in 75 either direction while said shaft is stationary, means for unlocking said member whenever said shaft is rotated in either direction, and means for rotating said shaft, substantially as set forth.

6. In apparatus of the character described, 80 the combination with a power shaft, of a car-supporting rotatable member loose thereon, means for coupling said member to said shaft for rotation therewith whenever the latter is rotated in either direction, and means for automatically locking said member whenever said shaft ceases moving, substantially as set forth.

7. In apparatus of the character described, 85 the combination with a shaft, a sheave loose thereon, a fixed member surrounding said shaft, a brake band therein, a lever for actuating said brake band, and a member fixed to said shaft for actuating said lever into inoperative position, substantially as set forth.

8. In apparatus of the character described, 90 the combination with a shaft, a sheave loose thereon, a fixed member surrounding said shaft, a brake band therein, a lever for actuating said brake band, a member fixed to said shaft for actuating said lever into inoperative position, and means secured to said sheave for actuating said lever into operative relation to said brake band, substantially as set forth.

9. In apparatus of the character described, 95 the combination with a shaft, a sheave loose thereon having two lever-actuating means thereon, and a locking lever, adapted to be actuated into locking position by either of said lever-actuating means, substantially as set forth.

10. In apparatus of the character described, 110 the combination with a shaft, a sheave loose thereon having lever-actuating means on either side of said shaft, a locking lever interposed between said lever-actuating means, and a member fixed to said shaft and adapted to operate said lever, substantially as set forth.

11. In apparatus of the character described, 115 the combination with a shaft, a sheave loose thereon having lever-actuating means on either side of said shaft, a locking lever having portions respectively interposed in the path of said lever-actuating means in either direction of rotation, said lever and portions thereof being so positioned that contact of either of said portions 120

4

by either of said actuating means moves said lever into locking position, substantially as set forth.

12. In apparatus of the character described, the combination with a shaft, a sheave loose thereon having lever-actuating means on either side of said shaft, a locking lever having portions respectively interposed in the path of said lever-actuating means in either direction of rotation, and a member fixed to said shaft having a portion situated between and adapted to contact one or the other of said portions, on rotation of said shaft, to rotate said lever into unlocking position, substantially as set forth.

13. In apparatus of the character described, the combination with a shaft, a sheave loose thereon, means for locking said sheave against rotation, comprising a lever having locking and unlocking positions, means secured to said sheave on one side of said lever, adapted, on rotation of said sheave in one direction, to force said lever into locking position, and means secured to said shaft, on the other side of said lever, adapted, on rotation of said shaft in the opposite direction, to contact said lever and force the same into unlocking position, substantially as set forth.

14. In apparatus of the character described, the combination with a shaft, a sheave loose thereon, means for locking said sheave against rotation, comprising a lever having locking and unlocking positions, means secured to said sheave on one side of said lever, and means secured to said shaft on the other side of said lever, adapted, on rotation of said shaft in one direction, to contact and move said lever into unlocking

position and to rotate said sheave through contact of said lever with said means secured to said sheave, substantially as set forth.

15. In apparatus of the character described, the combination with a shaft, a sheave loose thereon, means for locking said sheave against rotation, comprising a lever having a locking and an unlocking position, means secured to said shaft adapted, on rotation of said shaft in either direction, to contact said lever and move the same to unlocking position, and means, secured to said sheave, adapted on rotation of said sheave in either direction, when said shaft is stationary, to contact the lever and move the same to locking position, substantially as set forth.

16. In apparatus of the character described, the combination with a shaft, a sheave loose thereon, means for locking said sheave against rotation, comprising lever means, having locking and unlocking positions, means secured to said shaft, adapted, on rotation of said shaft in either direction, to contact said lever means and move the same to unlocking position, and means, secured to said sheave, adapted to be contacted by said lever means in unlocking position of the latter, on rotation of said shaft in either direction, to connect said sheave for rotation to said shaft, substantially as set forth.

This specification signed and witnessed this 28th day of March, 1914.
